UNITED STATES PATENT OFFICE.

GEORGE MURDOCH, OF BROOKLYN, NEW YORK.

BONE-BLACK OVEN.

SPECIFICATION forming part of Letters Patent No. 314,866, dated March 31, 1885.

Application filed June 14, 1884. (No model.)

To all whom it may concern:

Be it known that I, GEORGE MURDOCH, of Brooklyn, in the county of Kings and State of New York, have invented a new and useful 5 Improvement in Bone and Bone-Black Ovens, of which the following is a full, clear, and exact description.

Reference is to be had to the accompanying drawings, forming a part of this specification, 10 in which similar letters of reference indicate corresponding parts in all the figures.

Figure 1, Sheet 1, is a plan view, partly in section, of my improvement. Fig. 2, Sheet 2, is a front elevation of the same, partly in section, through the line *x x* of Fig. 1. Fig. 3, 15 Sheet 2, is a sectional side elevation of a part of the same, taken through the line *y y*, Fig. 2.

My invention is an improvement in the class 20 of ovens adapted for making or revivifying bone-black; and it consists in a certain combination of parts, as hereinafter described and claimed.

For convenience, and to economize space in carrying my improvement into practical effect, 25 I propose to build two sets of furnaces and ovens in one stack, the said sets being placed back to back upon the opposite sides of a division-wall, as shown in Figs. 1 and 3.

A is a furnace, at the side of which are 30 placed three or more ovens, B, as shown in Figs. 1 and 2, and which is provided with a door, C, a grate, D, and an ash-pit, E, in the ordinary manner. Each oven B is provided with a chamber, F, to receive the bone-black, 35 which chamber has an inclined floor, G, so that the bone-black can be readily withdrawn through the discharge-opening H in the front wall of the oven. The discharge-opening H is closed by a sliding gate, I, or other suitable door. The oven B is provided with a 40 door, J, through which the bones or foul bone-black is introduced. The doors J of the ovens and receiving-chambers B F are applied to an iron plate, K, secured in place by stay-rods L, which also serve to strengthen the 45 ovens. The lower parts of the side walls of each oven B are drawn inward, forming a narrow bottom, to which a grate-like form is given by the tie-bricks M. The tie-bricks M 50 are placed at a little distance from each other,

and are strengthened in position by iron bars N, placed beneath them and built into the walls.

Upon the bottom of the ovens B are placed sheet-iron slides O, to prevent the contents of the said ovens from dropping out before the burning has been completed. The outer ends of the slides O project through an opening in the lower part of or below the doors J, so that the ovens can be drawn without opening the 55 said doors and admitting air. In the walls, at the sides of the ovens B, are formed flues P, into which lead small upwardly-inclined passages Q from the said ovens. The openings of the lower passage Q in the combustion-chamber of the furnace A are covered by a wall, R, placed at a little distance from the said openings, as shown in Figs. 1 and 2.

S are the covers of the ovens B, which covers also serve as a part of the bottom of the 70 flue T, leading from the upper part of the combustion-chamber of the furnace A to the smoke-stack U, and into which the flues P open, as shown in Figs. 2 and 3.

V is the cover of the flue T, which is kept 75 in place by the stay-rods L. With this construction the contents of the oven B next the furnace A will be fired from the said furnace by heat passing through the division-wall, and each succeeding oven will be fired from the 80 preceding one in the same manner, the smoke and the incombustible gases generated by the combustion of the animal matter upon and in the bones, and the oil and other substances in the bone-black being reburned, escaping 85 through the passages Q and flues P into the furnace-flue T, and passing thence into the smoke-stack U.

I do not claim, broadly, a bone-black oven or retort arranged alongside a furnace proper, 90 nor one through or around which the products of combustion may pass, nor one contracted at the bottom and provided with a device for controlling the discharge of contents.

Having thus described my invention, I claim 95 as new and desire to secure by Letters Patent—

1. In a bone-black oven, the combination, with the furnace A and ovens proper, B, of narrow vertical flue P, extending between said ovens, and the small lateral passages Q, lead- 100

ing upward from ovens to flues, as shown and described.

2. In bone and bone-black ovens, the oven B, made, substantially as herein shown and described, with a contracted grate-bottom covered with a slide, substantially as herein shown and described, whereby the oven can be readily drawn, as set forth.

3. In bone and bone-black ovens, the com-

bination, with the ovens B, of the receiving-chambers F, having inclined bottoms G, substantially as herein shown and described, whereby the bone-black can be allowed to cool before being exposed to the air, as set forth.

GEORGE MURDOCH.
